(57) **CLAIM**

The ornamental design for a light fixture, as shown and described.

DESCRIPTION

FIG. 1 is a perspective view of a light fixture showing my new design;

FIG. 2 is a top view of the light fixture shown in FIG. 1;
FIG. 3 is a front perspective view of the light fixture shown in FIG. 1, with the top portion shown removed;
FIG. 4 is a side view of the light fixture shown in FIG. 1, with the other side view being a mirror image thereof; and,
FIG. 5 is a bottom view of the light fixture shown in FIG. 1.
